Inventor.

Jan Crnoev.
By Frank J. Karan
Attorney.

UNITED STATES PATENT OFFICE.

JAN CRNOEV, OF ST. LOUIS, MISSOURI.

COLLAR FASTENER.

Application filed April 2, 1923. Serial No. 629,343.

To all whom it may concern:

Be it known that I, JAN CRNOEV, a subject of the King of Servia, residing in the city of St. Louis and State of Missouri, have 5 invented certain new and useful Improvements in Collar Fasteners, of which the following is a specification.

My invention relates to collar fasteners, and, more particularly, to separable fasteners adapted for use in connection with soft 10 collars to prevent the points from spreading, and, it is a distinct and practical improvement to overcome certain practical objections to, and defects in the present universal types of separable collar fasteners or point holders.

The object of my present invention is to provide an extensible and separable bar whose length may be adjusted for the purpose of accommodating different shapes of 20 collars and holding the points or wings thereof at the desired distance apart.

A further object of the invention is the provision of a pair of resilient pin holder 25 or coupling sleeves for uniting the fastener pins and holding them in their adjusted position by frictional contact with the inner surface of the sleeves.

A further object of the invention is to 30 slightly wave the fastener pins along their length to prevent casual displacement in the coupling sleeves.

With the above and other objects in view, the invention consists in the novel features 35 of construction, arrangement and combination of parts hereinafter more fully described and finally pointed out in the claims hereto appended.

Referring to the accompanying drawing 40 forming a part of this specification, wherein like characters of reference denote similar parts throughout the several views:

Fig. 1, is a front view of a soft collar showing my improved holder applied 45 thereto.

Fig. 2, is a perspective view of the coupling member of the holder.

Fig. 3, is a perspective view of one of the holder pins.

Fig. 4, is a detail showing one of the pins 50 as being applied to the collar.

Fig. 5, is a front view of a collar showing a modified form of holder applied thereto.

Fig. 6, is a perspective view of the modified form of pin.

Fig. 7, is a plan view of the coupling blank.

Fig. 8, is a rear elevation of the coupling after the blank has been folded.

Fig. 9, is an enlarged end view of Fig. 8.

Fig. 10, is an enlarged vertical sectional view taken through one of the sleeves of Fig. 8.

Fig. 11, is a modified form of coupling 65 sleeve shown in Fig. 1.

In carrying out the aim of my present invention, I employ a coupling member made from a single strand of suitable spring wire and so formed by coiling the wire as to 70 provide two opposed coupling sleeves 1 united by a central integral wire connection 2. The sleeves 1, while opposed, are not arranged in longitudinal alignment, but are slightly offset in parallel alignment, as clearly 75 shown in Fig. 1. The outer end of each sleeve 1 is provided with a tapered cuff or pin guide 3. The cuffs are tapered on two sides and are substantially flat on the remaining two sides, as clearly shown in 80 Fig. 2.

The reference character 4 indicates a pair of fastening or holder pins which are preferably waved or slightly corrugated along their length, although not necessarily so. 85 The fastening or holder pins 4 are each provided at one end with a suitable point 5 and at their opposite or outer ends with a suitable head 6 formed by coiling the wire a plurality of turns. Two pins 4 are used 90 with one coupling member as one coupling member is provided with two pin receiving sleeves. The pins are guided into the sleeves through the tapered cuffs thereof.

The pins are first caused to penetrate the 95 points of the collar designated 7 and the heads 6 thereof are brought into contact with the outer face of the collar. The pins 4 are then given a circular twist which will cause the coiled heads 6 thereof to screw themselves into the material of the soft cloth collar 7, thereby securely anchoring the pins 100

4 to the points of the collar 7, thereby preventing accidental loss of the pins from any cause.

After the pins 4 have been applied to the 5 points of the collar 6, they are each forced into a coupling sleeve 1 and they are held in their adjusted positions by frictional contact therewith, as is manifest. The pin 4 passing through one sleeve may also frictionally engage the peripheral surface of 10 the other sleeve thereby affording additional resistance by frictional contact of the pins with the sleeves.

In the modified form of my invention 15 shown in Figs. 5 to 10, of the drawings, the coupling member is made from a single sheet of metallic stock instead of wire and the sleeves 1 are formed by folding the wings 8, as clearly shown in Fig. 10, instead of 20 being formed by coils of wire. The wings 8 are integral with a central section 9, which is equivalent to the wire connection 2, in Fig. 2. The outer end of each sleeve 1 is provided with a cuff shaped pin guide 3, 25 as shown in Figs. 5, 8 and 9, formed by folding opposite edges of the sleeve extensions, which are designated 10, in Fig. 7. The coupling pins 4 shown in Fig. 6, are shown as provided with a non-coiled head 6, al- 30 though a coiled head 6 may be formed on one end of the pins used with the modified form of coupling member. The coupling sleeves 1 of the modified form of coupling member frictionally and yieldingly engage 35 the pins 4 which may be non-waved or corrugated as shown in Fig. 6, or waved or corrugated, as shown in Fig. 3.

In Fig. 11, I have shown a modified form 40 of coiled spring wire coupling, the same being in every respect the same as the coupling shown in Fig. 1, with the exception that I eliminate the sleeve cuffs or pin guides 1' which are only employed for the purpose of guiding the fastening pins into the sleeves 1.

In either form of invention shown, it is 50 evident, that the coupling member is provided with opposed sleeves 1 to slidably and frictionally receive and engage the holding pins 4 which are anchored to the points 7 of the collar.

From the foregoing description, it is apparent that I provide a collar holder which 55 is simple and comparatively inexpensive to manufacture and highly efficient for the purpose intended.

The many advantages of the herein described invention will readily suggest themselves to those skilled in the art to which it 60 appertains.

I do not desire to be understood as limiting myself to the exact details of construction and arrangement as herein described and illustrated, as it is manifest that variations and modifications may be made with-

out departing from the spirit and scope of my invention and the terms of the following claims, hence I wish it to be understood that I reserve the right to make any such changes, or modifications as may fairly fall 70 within the scope of the appended claims when fairly construed.

What I claim is:

1. A collar holder comprising a coupling member formed with two normally non-aligned coiled wire sleeves, a pin for each sleeve and a coiled head for each pin. 75

2. A collar holder comprising a coupling member formed with two normally non-aligned coiled wire sleeves, means for connecting said sleeves, a pin for each sleeve having slidable and frictional engagement therewith and a coiled head for each pin. 80

3. A collar holder comprising a flexible resilient coupling member consisting of two sleeves formed by coiling a single strand of wire, a pin for each sleeve and a coiled head for each pin. 85

4. A collar holder comprising a flexible resilient coupling member consisting of two sleeves formed by coiling a single strand of wire, a pin for each sleeve having slidable and frictional engagement therewith and a coiled head for each pin. 90

5. A collar holder comprising a coupling member having a pair of opposed friction sleeves, a removable pin for each sleeve, a head for each pin, said pins having waves along their length and adapted to enter and pass through the sleeves of the coupling member for uniting the pins after they are 95 applied to a collar. 100

6. A collar holder comprising a coupling member provided with a pair of closely coiled wire sleeves disposed out of axial alignment 105 with each other and connected by means of a portion of the same strand from which the sleeves are formed, a pin for each sleeve, a coiled head for each pin and a pin guide cuff for each sleeve forming a part of the 110 coupling member.

7. A collar holder comprising a coupling member formed of a single piece of stock to provide two non-aligned coiled wire sleeves united by an integral part of the 115 wire forming the sleeves, a pointed pin slidably and frictionally receivable in and through each sleeve to retain the pins in adjusted relation and a coiled head for each pin. 120

8. A collar holder comprising a coupling member formed of a single piece of stock to provide two non-aligned sleeves, a pin frictionally slidable in and through each sleeve to retain the parts in adjusted relation and a coiled head for each pin adapted to lock the pins to the collar. 125

9. An extensible and separable collar fastener comprising a coupling member consisting of two normally non-aligned united 130

coiled wire sleeves, means integral with the sleeves for uniting them, a fastening pin passable through each sleeve and held in adjusted relation with its respective sleeve by frictional contact therewith and a coiled head for each fastening pin.

10. In combination with the points of a soft cloth collar, of a pointed pin for connection to each point of the collar, a coiled

head for each pin and a coupling member 10 consisting of two fixed non-aligned sleeves for uniting the pins and holding them in their adjusted relation with their respective coupling member sleeves.

In testimony whereof, I have hereunto 15 signed my name to the specification.

JAN CRNOEV.
